UNITED STATES PATENT OFFICE.

SILAS R. DIVINE, OF LOCH SHELDRAKE, NEW YORK, ASSIGNOR TO THE
REND ROCK POWDER COMPANY, OF NEW JERSEY.

EXPLOSIVE COMPOUND

SPECIFICATION forming part of Letters Patent No. 289,759, dated December 4, 1883.
Application filed July 23, 1883. (No specimens.)

To all whom it may concern:

Be it known that I, SILAS R. DIVINE, of
Loch Sheldrake, Sullivan county, State of New
York, and a citizen of the United States, have
5 invented an Improved Explosive Compound,
of which the following is a full, clear, and ex-
act specification.

My invention consists in an explosive com-
10 pound for use, chiefly, in blasting, composed of
a solid ingredient—such as chlorate of potash—
and a liquid ingredient consisting of a mixture
of “dead-oil” and nitro-glycerine, which in-
gredients are in themselves non-explosive by
15 percussion, and hence may be with safety
handled and transported separately, and which
may be combined to form the explosive by
allowing the solid to absorb the liquid ingre-
dient, substantially in the proportions and as
20 and for the purpose set forth.

The object of my invention is to produce a
25 compound which is susceptible to explosion,
and one the strength or explosive force of
which may be graded or regulated at pleasure.

The solid ingredient of my compound con-
25 sists, preferably, of crushed or powdered chlo-
rate of potash, although perchlorate or per-
manganate of potash may be thus employed.
The liquid ingredient of my compound I com-
pose of preferably two parts of dead-oil to one
30 part of nitro-glycerine, as these proportions
constitute a mixture which is capable of being
handled and transported safely, and which at
the same time, when combined with the solid
ingredient, in the proportions named, unite
35 most effectively therewith to form an explo-
sive. The theoretical proportions in which the
chlorate of potash and the said mixture com-
bine most effectively, as stated, are about five
parts of the chlorate of potash to one part of
40 the mixture; but for the purpose of somewhat
decreasing the sensitiveness of the compound

in its practical use, it is found desirable to
sometimes decrease the said proportions to
about four parts of the chlorate of potash to
one of the mixture. The exact theoretical pro-
portions may therefore be varied from and
still an efficient explosive be produced. 45

The proportions of the dead-oil and the
nitro-glycerine which are indicated as pref-
erable in the mixture constituting the liquid
ingredient may be varied somewhat; but it is
not desirable that the nitro-glycerine in the
mixture should be decreased below about
20 twenty per cent., as its effect in the compound
thereby apparently disappears, while it is not
desirable that it should be increased above fifty
or sixty per cent., as its “sensitizing” effect
is then too greatly augmented for the purposes
of this invention. 55

Other fluid hydrocarbons than dead-oil 60
which are practically non-volatile in a free
state at ordinary temperatures, and which are
solvents of nitro-glycerine, or such nitro com-
pounds as nitro-benzole, may be used with the
nitro-glycerine to form the described mixture 65
constituting the liquid ingredient of the com-
pound.

What I claim as my invention, and desire to
secure by Letters Patent, is—

The herein-described explosive compound, 70
composed of chlorate of potash, constituting
the solid ingredient, and dead-oil and nitro-
glycerine, substantially in the proportions set
forth, constituting the liquid ingredient, the
said solid and liquid ingredients being me-
chanically united, substantially in the propor-
tions and as and for the purpose specified. 75

SILAS R. DIVINE.
